UNITED STATES PATENT OFFICE

LAWRENCE C. JOHNS, OF RICHMOND, VIRGINIA, ASSIGNOR OF ONE-HALF TO PAUL C. MORELAND, OF RICHMOND, VIRGINIA

RESERVOIR FOUNTAIN PEN

Application filed December 20, 1926. Serial No. 155,939.

My invention relates to new and useful improvements in reservoir fountain pens and more particularly to an arrangement whereby a reservoir or well of relatively large capacity is provided, to which is operably connected one or more fountain pens, so that the ink supply may last for many months depending of course upon the number of pens connected to the reservoir, the amount of use of the pens and the size of the reservoir.

Another object of the invention is to provide a reservoir of neat and attractive form, so that the same may be placed on a desk or table and provide a pleasing appearance. To 15 the reservoir will be operably connected, one or more tubes, which in turn are arranged internally, as will be hereinafter described, so that a proper supply of ink is furnished through the one or more tubes connected with 20 the reservoir to the pens.

Another object of the invention is to provide a reservoir for a large supply of ink, from which extends a plurality of tubes while operably fastened with each tube is a fountain 25 pen or portion thereof, which pen will always be ready for service and at the same time will not leak or discharge while the pen is not in use.

With these and other objects in view, the 30 invention consists in certain new and novel arrangements and combinations of parts as will be hereinafter more fully described and pointed out in the claims.

Referring now to the drawings showing a 35 preferred embodiment of the invention,

Fig. 1 is a view of my improved reservoir fountain pen, the base and reservoir being shown in section.

Fig. 2 is a perspective view of the device.

Fig. 3 is an enlarged detailed sectional view 40 of the fountain pen, showing the manner of attaching the tube thereto, and

Fig. 4 is an enlarged sectional view showing 45 a slight modification, the device being arranged for a multiplicity of feeding tubes for fountain pens.

Referring now more specifically to the several views, there is shown a standard or support 1, which may be of nickel or bronze or 50 any other suitable material while the base of

the support 2 may be weighted and provided with a layer of felt 3, so that the base will not scratch or mar the desk on which it rests.

The upper end of the support may be enlarged as at 4, and then extend outwardly as 55 at 5, so that a bottle 6 or other form of well or reservoir may be placed in an inverted position in the support. I may also place a strap 7 over the top of the well or reservoir 6, which may be hinged as at 8 to the rim 9 of the supporting bowl 5 and in turn fit under the opposite side of the rim to effectively hold the reservoir 6 in position.

The bottle or reservoir 6 may have a central opening 10 in its upper surface, in which 65 there may be placed a cork 11 and the band 7 may be shaped to straddle this opening and cork as seen in Fig. 2. Also in this band 7 there may be formed or struck up a pair of 70 clips 12, so that the pen proper 13, when not in use, may rest in these clips.

The neck 14 of the bottle 6 may be provided 75 with a cork or stopper 15, in which there will be placed a porcelain or glass tube 16, while to tightly seal the cork or stopper within the bottle, I may place a small quantity of sealing wax 17 about the neck of the bottle and the cork, as may be seen.

Fitting up within the porcelain or glass 80 tube 16, I have shown a rubber tube 18, which may be flared as at 19, so that even though a pulling strain be placed on this tube, it would not disengage from the tube 16 within the cork.

The rubber tube 18 may then extend downwardly and centrally of the support 1, and out through the bushing 20, and at its other end is securely fastened about a part of the inner barrel 21 of the fountain pen.

Most of the fountain pens now in use may 85 be fastened to this tube, that is pens of the self filling type, as the little rubber chamber not shown that supplies the ink of the self filling fountain pens may be removed and the present tube attached to that part of the 90 fountain pen to which the small tube was formerly attached. Of course special formed fountain pens proper may be made to suit the other conditions of the present invention.

I have found by experiment that certain 100

provision must be made to retard the ink flowing to the fountain pen, and for this purpose I provide a flax wick 22 of cord-like form, which wick is provided with a plurality of strippers 23, each fitting the tube 18 snugly and provided with a central aperture 24 through which the wick 22 may pass.

I have found however, that if I provide a plurality of strippers 23, or small washers 10 and place these within the tube, the flow of ink will be greatly reduced. Furthermore, these strippers are provided with a small central aperture 24, so that the wick 22 may extend from the neck or stopper of the reservoir through the entire length of tube and terminate at a point 25 adjacent the groove or passage-way 26 formed in the end of the fountain pen beneath the nib or pen point.

In other words the ink may feed along this 20 wick and through the strippers while the strippers in turn form what might be termed several chambers within the tube.

It might also be here mentioned, that although I have tried various forms of wicks, 25 the only ones that permit the ink to feed smoothly and prevent the same from overflowing or leaking are those made of flax.

I have also found that the size of the passage 26 in the pen must bear a certain ratio 30 to the size of the bottle or reservoir.

In other words the flow is dependent upon the diameter of the tube and the head and if a small reservoir is used, a small passage-way in the pen may be used, whereas, if the 35 reservoir is designed to hold say a quart of ink, the passage-way must be correspondingly smaller.

In Fig. 1 I have shown a small wire coil 27 that may fit in the end of the fountain pen 13 40 proper, so that there will be no danger of cutting off the ink supply when the same is in use, by reason of a sharp bending of the tube at this point.

In Fig. 4 I have shown a slightly modified 45 form, in that in this instance the stopper 28 may be provided with a plurality of openings 29, into which there may be inserted a plurality of tubes 30, each of which is provided with its respective wick 31 and the strippers 50 32. To the other end of each of these tubes, of course, will be secured a fountain pen, so that a number of these pens may be in use at the same time, from one and the same source 55 of ink supply.

It is to be understood that the shape of the reservoir or the shape of the base or the appearance of the device as a whole does not enter into the invention, as both the base and the reservoir may be of any preferred or desired shape or form.

The invention per se relates to the attachment of an ordinary form of fountain pen to an elongated tube in which a wick is placed 60 and in which tube there is placed a number of strippers for retarding the flow of ink

through the tube and said tube leading to a supply of ink which may flow by gravity under control to the pen or pens.

When the pen or pens are not in use they may be placed in clips at the top of the support, so that there will be no possible chance of any over-flow of the ink, although I have found in actual practice that even though the pen is not in use it may be laid on the table below the reservoir level and the ink will not 75 over-flow or leak from the pen.

The device is one that may be used by one or more persons at one time, that is, if a plurality of pens are provided and it will not be necessary to supply the ink except at long 80 intervals.

Of course the cork 11 should be loosened at odd times, so that air may enter the reservoir.

Many changes might be made from the preferred form without in any way departing 85 from the spirit and scope of the invention.

Having thus described my invention what I claim as new and desire to secure by Letters Patent is:

1. A reservoir fountain pen comprising a 90 reservoir proper, a flexible tube connected with the reservoir, a wick threaded through the tube, stripper members located in the flexible tube and surrounding the wick at spaced intervals and holding the surface of the wick spaced from the inner surface of the tube, and a pen carried at the free end of the tube.

2. A reservoir fountain pen comprising a 100 reservoir proper, a flexible tube connected with the reservoir, a wick of flax fibre threaded through the tube, stripper members located in the flexible tube and surrounding the wick at intervals along the length of the strands of the flax fiber and holding the surface of the wick spaced from the inner surface of the tube, and a pen carried at the free end of the tube.

3. A reservoir fountain pen comprising, a 110 flexible tube, a reservoir connected with one end of the tube, a wick of flax fibre less in diameter than the interior diameter of the tube, said wick being threaded through the flexible tube, and a pen carried at the other end of the flexible tube.

In testimony whereof I affix my signature.
LAWRENCE C. JOHNS.
